UNITED STATES PATENT OFFICE

147,594

DESIGN FOR A GARMENT HANGER

James D. McDonald, Los Angeles, Calif.

Application June 29, 1946, Serial No. 131,204

Term of patent 3½ years

(Cl. D80—8)

To all whom it may concern:

Be it known that I, James D. McDonald, a citizen of the United States, residing at Los Angeles, in the county of Los Angeles and State of California, have invented a new, original, and ornamental Design for a Garment Hanger, of which the following is a specification, reference being had to the accompanying drawing, forming part thereof.

In the drawing:

Fig. 1 is a top plan view of a garment hanger showing my new design;

Fig. 2 is a front elevation of the garment hanger; and

I claim:

The ornamental design for a garment hanger, as shown.

JAMES D. McDONALD.
